(57) **CLAIM**

The ornamental design for caliper, as shown and described.

DESCRIPTION

FIG. 1 is a front, right-side, top perspective view of a first embodiment of the caliper;

FIG. 2 is a front elevational view thereof;
FIG. 3 is a top plan view thereof;
FIG. 4 is a right-side elevational view thereof;
FIG. 5 is a left-side elevational view thereof;
FIG. 6 is a rear elevational view thereof;
FIG. 7 is a bottom plan view thereof; and
FIG. 8 is a front, left-side, bottom perspective view thereof.
FIG. 9 is a front, right-side, top perspective view of a second embodiment of the caliper;
FIG. 10 is a front elevational view thereof;
FIG. 11 is a top plan view thereof;
FIG. 12 is a right-side elevational view thereof;
FIG. 13 is a left-side elevational view thereof;
FIG. 14 is a rear elevational view thereof;
FIG. 15 is a bottom plan view thereof; and
FIG. 16 is a front, left-side, bottom perspective view thereof.
FIG. 17 is a front, right-side, top perspective view of a third embodiment of the caliper;
FIG. 18 is a front elevational view thereof;
FIG. 19 is a top plan view thereof;
FIG. 20 is a right-side elevational view thereof;
FIG. 21 is a left-side elevational view thereof;
FIG. 22 is a rear elevational view thereof;
FIG. 23 is a bottom plan view thereof; and
FIG. 24 is a front, left-side, bottom perspective view thereof.
FIG. 25 is a front, right-side, top perspective view of a fourth embodiment of the caliper;
FIG. 26 is a front elevational view thereof;
FIG. 27 is a top plan view thereof;
FIG. 28 is a right-side elevational view thereof;
FIG. 29 is a left-side elevational view thereof;
FIG. 30 is a rear elevational view thereof;
FIG. 31 is a bottom plan view thereof; and
FIG. 32 is a front, left-side, bottom perspective view thereof.
The broken lines depict environmental subject matter only
and form no part of the claimed design.
